DESIGN FOR A PARTITIONED TRAY

Horace W. Raymond, Waterville, Maine

Application June 20, 1945, Serial No. 120,207

Term of patent 14 years

(Cl. D44—10)

To all whom it may concern:

Be it known that I, Horace W. Raymond, a citizen of the United States, residing at Waterville, in the county of Kennebec, State of Maine, have invented a new, original, and ornamental Design for a Partitioned Tray, of which the following is a specification, reference being had to the accompanying drawing, forming part thereof.

Fig. 1 is a perspective view of a partitioned tray showing my new design, and

Fig. 2 is a section on the line 2—2 of Fig. 1.

I claim:

The ornamental design for a partitioned tray, as shown.

HORACE W. RAYMOND.
